UNITED STATES PATENT OFFICE.

THOMAS B. CARRICK, OF JACKSONVILLE, FLORIDA.

DESIGN FOR A CONCRETE RAILING.

Application filed December 6, 1924. Serial No. 11,606. Term of patent 7 years.

To all whom it may concern:

Be it known that I, THOMAS B. CARRICK, a citizen of the United States, residing at Jacksonville, in the county of Duval and State of Florida, have invented a new, original, and ornamental Design for Concrete Railing, of which the following is a specification, reference being had to the accompanying drawing, forming a part hereof.

In the drawing, Figure 1 is a side elevation of a railing, showing my new design.

Figure 2 is a top plan view of a railing, showing my new design.

What I claim is:

The ornamental design for a concrete railing, as shown.

THOMAS B. CARRICK.
